FOLDABLE EXTENSION DEVICE

Filed April 30, 1930

INVENTOR,
Wifred J. Roy
Barlow & Barlow
ATTORNEYS.

UNITED STATES PATENT OFFICE

WILFRID J. ROY, OF EAST ORANGE, NEW JERSEY, ASSIGNOR TO GEMEX COMPANY, OF NEWARK, NEW JERSEY, A CORPORATION OF NEW JERSEY

FOLDABLE EXTENSION DEVICE

Application filed April 30, 1930. Serial No. 448,561.

This invention relates to a foldable extension device frequently called a buckle, for temporarily enlarging the encircling size of a wrist band, bracelet or the like, and has for its object to provide an adjustment by which the encircling size of the bracelet in which it is connected may be changed.

A further object of the invention is to provide a construction in which the bracelet may be detached from the extension device for removing a link or other manipulation and adjustably secured thereto.

A still further object of the invention is to provide a device which will be thin, compact and comfortable to wear, and which may be securely held in folded position.

A still further object of the invention is to provide a simple construction by which these desirable results are accomplished, and one which may be easily manufactured in multiple units and assembled without the use of solder.

With these and other objects and advantageous features in view, the invention consists of a novel arrangement of parts more fully disclosed in the detailed description following, in conjunction with the accompanying drawings, and more particularly set forth in the appended claims.

30 In the drawings:

Fig. 1 is a top plan view of the extension device connected in a bracelet which is formed of open frame shape links;

Fig. 2 is a bottom plan view thereof;

35 Fig. 3 is a bottom view with the device in extended position;

Fig. 4 is a section on line 4—4 of Figure 2;

Fig. 5 is a section on line 5—5 of Figure 2;

Fig. 6 is a section on line 6—6 of Figure 3;

40 Fig. 7 is a section on line 7—7 of Figure 3;

Figs. 8, 9, 10 and 11 are perspective views of certain detail parts which are joined together;

Fig. 12 is a side elevation showing the assembled construction in a position to permit adjustment of the connecting member.

In the use of link bracelets, it is desirable to use a foldable extension device for temporarily enlarging the bracelet, and by providing an adjustment for the encircling size

which will cooperate to continue the appearance of the links to which the device is attached, which I have accomplished in a frame link bracelet by providing a U-shaped member having substantially the appearance when its ends are connected to the extension device of one of the frame links to which it is attached, and have utilized this structure as a convenient means for providing an adjustment for the encircling size of the bracelet with the other sections folding into the adjustable means and between the ends of this U-link so that a compact assemblage may be formed when in folded position without unduly increasing the thickness of the device to the discomfort of the user; and the following is a detailed description of the present embodiment of this invention illustrating the preferred means by which these advantageous results may be accomplished.

With reference to the drawings, 15 designates the frame links of the bracelet which are hingedly joined together by a connector 16, the end link 17 being permanently attached to the device, and the end link 18 being joined to the connector member 19 which is a part of the connecting device, and which is adjustable with reference to the sections, as will more fully hereinafter be described.

The extension device consists of a channel section 20 having a top wall 21, side walls 22 with turned edges or flanges 23. A plate section 24 is provided with trunnions 25 extending into the openings 26 in the side walls 22 to hinge the same thereto, and about the trunnions 25 there is also pivotally mounted a channel member 27 having a top wall 28, side walls 29, and lateral extensions 30 provided with ears 31 having openings 32 therein through which the trunnions 25 extend to pivotally mount this member in the channel section 20.

The side walls of the channel member 27 are provided with openings 33 arranged opposite each other in pairs to receive the detents 34 of the connector member 19 in any one of the pairs of oppositely disposed openings 33 which may be selectively engaged to adjustably connect this connector member 19 thereto in assembled relation. Referring

to Figure 3, the channel section 20 receives the channel section 27 with the corresponding top and side walls thereof similarly arranged and in parallel relation, and the member 27 being of a width less than the channel section 20 causes the side walls 22 and 29 to be spaced, in which space the ends of the connector 19 are received between these side walls, and beneath the inturned flanges 23 to prevent either the connector member 19 or the channel member 27 from being lifted from the section 20 to be swung about the pivotal mounting above referred to. However, the walls 22 are sufficiently resilient to spread and permit the member 19 to be swung about its trunnions 34 or together with the section 27 swung about the pivotal mounting 25 therefor.

The section 35 is hingedly connected to the section 24 and the sections 36 and 37 similarly joined in hinged series so that they may be folded together one upon the other and together with the section 24 housed between the side walls 29 of the channel member 27, as shown in Figures 2 and 4. The section 37 is provided with lateral extensions or wings 38 rolled inwardly as illustrated in Figure 5, which resiliently engage and snap between the walls 22 and back of its inturned portion 23 to lock the sections in folded position. These portions 38 are extended sufficiently laterally to avoid engagement with the walls 29 of the connecting member and to permit compact assembly of the parts. The section 37 is also provided with a hook 39 which is rolled about the end link of the bracelet 17 to secure this end to the device.

There is sufficient resilient action between the connector member 19 and the channel member 27 to permit springing of the parts for detachment or adjustment of the same therealong, but such adjustment is prevented when the channel member is against the section 20 and the member 19 beneath the in-turned edges or flanges of the walls 22, the same being moved to a position substantially as illustrated in Figure 12, to permit the adjustment when desired.

While I have described certain construction forms which embody the principles of my invention, it is obvious that other desired changes in arrangement may be made within the spirit and the scope of the invention as defined in the appended claims.

I claim:

1. In an extension device, a plurality of sections hinged together to fold one upon the other, a member hingedly connected to one of said sections upon the hinge connection between two of said sections, means for detachably securing a bracelet end to said member, and means for securing the other end of the bracelet to one of said sections.

2. In an extension device, a plurality of sections hinged together to fold one upon the

other, a member hingedly connected to one of said sections upon the hinge connection between two sections, means for detachably securing a bracelet end to said member, means to lock said means and member in position when said member and the section hinged thereto are in contiguous relation regardless of the extended or contracted position of the sections, and means for securing the other end of the bracelet to one of said sections. 70

3. In an extension device, a plurality of sections hinged together to fold one upon the other, a member hingedly connected to one of said sections on the hinge connection between two of said sections, means for adjustably securing a bracelet end to said member, and means for securing the other end of the bracelet to one of said sections. 80

4. In an extension device, a plurality of sections hinged together to fold one upon the other, a member hingedly connected to one of said sections upon the hinge connection between two of said sections and provided with side walls having pairs of oppositely disposed openings, a U-shaped connector member having detents at the ends of the arms of the U to be received in the selected pair of openings. 85

5. In an extension device, a plurality of sections hinged together to fold one upon the other, a member hingedly connected to one of said sections upon the hinge connection between two of said sections and provided with side walls, a connector member, means between said side wall and connector member to adjustably secure the same together, the other of said sections being of a width to be received between said side walls, and means for securing said sections in folded position. 95

6. In an extension device, a channel section having side walls with inturned edges, a channel member of a width less than that of said section pivoted to said section to position its side walls parallel with the walls of said channel section, a connector member having arms pivoted to the walls of said channel member and held between said side walls by the inturned edges of the walls of said section. 100

7. In an extension device, a channel section having a top wall and side walls, inwardly extending flanges on the side walls, a channel member having a top wall and side walls with a plurality of pairs of oppositely disposed openings therein pivotally mounted in said section with its walls parallel and similarly disposed to the walls of said section, a U-shaped connector member having the arms of the U extending between the side walls of the respective channel section and member and beneath said flanges, detents on the said arms to extend into one pair of said openings to selectively position the connector member therein, the side walls of 110

5 said section retaining said arms with their detents in said opening but being resilient to prevent said connector members being swung from beneath said flanges and with said channel member about the pivot of the channel member, whereby disconnection or adjustment of the connector member may be effected.

8. In an extension device, a channel section, 10 means for adjustably connecting a bracelet end thereto comprising a channel member secured and housed within said section and a connector member adjustably secured to said channel member, a plurality of sections foldable one on the other hinged to said channel section and of a width to be housed within said channel member, means for releasably securing said sections in housed relation, and means for securing the other end of the bracelet to one of said sections.

9. In an extension device, a channel section, means for adjustably connecting a bracelet end thereto comprising a channel member secured and housed within said section and a connector member adjustably secured to said channel member, a plurality of sections foldable one on the other hinged to said channel section and of a width to be housed within said channel member, means 25 for releasably securing said sections in housed relation comprising laterally extending wings on one of said sections to engage the side walls of said channel section, and means for securing the other end of the bracelet to one of said sections.

10. In an extension device, a channel section, means for adjustably connecting a bracelet end thereto comprising a channel member pivotally secured and housed within 40 said section and a connector member adjustably secured to said channel member, a plurality of plate sections foldable one on the other hinged to said channel section and of a width to be housed within said channel member, means for releasably securing said sections in housed relation, and means for securing the other end of the bracelet to one of said sections.

11. In an extension device, a channel section, means for adjustably connecting a bracelet end thereto comprising a channel member pivotally secured and housed within said section and a connector member adjustably secured to said channel member, a plurality of plate sections foldable one on the other hinged to said channel section and of a width to be housed within said channel member, means for releasably securing said sections in housed relation comprising laterally extending wings on one of said sections to engage the side walls of said channel section, and means for securing the other end of the bracelet to one of said sections.

In testimony whereof I affix my signature.

65 WILFRID J. ROY.
